UNITED STATES PATENT OFFICE.

JOHN J. HEYS, OF LYNN, MASSACHUSETTS, ASSIGNOR, BY DIRECT AND MESNE ASSIGNMENTS, TO BRESNAHAN SHOE MACHINERY COMPANY, OF LYNN, MASSACHUSETTS, A CORPORATION OF MAINE.

CHAIN-STITCH SHOE-SEWING MACHINE.

No. 902,880.

Specification of Letters Patent.

Patented Nov. 3, 1908.

Application filed August 18, 1904. Serial No. 220,661.

To all whom it may concern:

Be it known that I, JOHN J. HEYS, of Lynn, in the county of Essex and State of Massachusetts, have invented certain new and useful 5 Improvements in Chain-Stitch Shoe-Sewing Machines, of which the following is a specification.

This invention relates to wax-thread chain-stitch shoe-sewing machines of the type used 10 in the manufacture of welt and turned shoes.

The object of the invention is to provide certain improvements in machines of the type mentioned for remedying defects which have proved undesirable, and for adding new 15 features which enhance the efficiency of such machines, increase their durability, simplify their construction, and increase their rapidity of operation.

The various features of the invention will 20 best be understood from the following description taken in connection with the drawings which illustrate one form or embodiment thereof, and said invention consists of the features, parts, and combinations as hereinafter defined by the claims.

On the drawings:—Figure 1 shows the left side elevation of a stitching machine embodying the several improvements of this invention. Fig. 2 shows the machine in front elevation. Fig. 3 is a right side elevation. Fig. 4 is an enlarged view of the stitching mechanism. Fig. 5 is an enlarged view of the shoe-feeding mechanism. Fig. 6 is a section on the line 6—6 of Fig. 4. Fig. 7 is a section on the line 7—7 of Fig. 5. Fig. 8 is a section on the line 8—8 of Fig. 5. Figs. 9, 10 and 11 illustrate the looper and its actuating mechanism. Fig. 12 is a section on line 12—12 of Fig. 11. Fig. 13 shows the work 25 gages and their locking mechanism. Fig. 14 is a section on the line 14—14 of Fig. 13. Fig. 15 is a plan view of the tension device. Figs. 16, 17 and 18 show the stitching mechanism in different positions. Fig. 19 is 30 a perspective view of the stitch-forming mechanism as it appears in the first stage of forming a new stitch. Figs. 20, 21 and 22 illustrate the successive stages in the formation of a stitch.

Referring to the drawings, the same reference characters indicate the same parts in all figures.

The machine illustrated by said drawings is but one embodiment of the invention, and

it will be understood that it may be varied in 55 many ways without departing from the spirit and scope of the invention; and it will be further understood that the terms and phraseology herein employed are for the purpose of description and not of limitation.

The machine as a whole comprises the head A which is adjustably supported on a suitable standard B. On the head A are supported the various operative portions of the mechanism, said operative mechanisms 60 all driven from the shaft 16, journaled in suitable bearings in the head. The head is arranged at an inclination to the horizontal, as described in my previous application Serial No. 172,352, filed Sept. 8, 1903, and it 65 has a rearwardly and upwardly projecting arm A', to which are secured forwardly projecting brackets A² in which the power-shaft 16 is journaled. This construction and arrangement of parts provides for the complete exposure of the operative mechanism 70 of the machine whereby they are easily accessible for the purposes of repair, cleaning, and adjustment.

For the purpose of transmitting power 80 from shaft 16 to the various operative mechanisms, such as the needle-actuating mechanism, awl-actuating mechanism, looper mechanism, etc., I employ cams either in the form of face or disk cams, which are suitably constructed for the purpose. The cams are in most cases conventionally illustrated, but it will be understood that in practice they are correctly constructed and timed so as to cause the various mechanisms 85 to operate in the manner hereinafter described.

The machine includes an awl, and mechanism for actuating the same, to cause it to penetrate the work and to feed the work with 95 a step-by-step movement; a needle and actuating mechanism therefor, a looper and mechanism by which the looper is caused to lay the thread around the barb of a needle, and to hold the thread substantially in alignment with the needle during the retrograde 100 movement thereof, suitable gages and actuating mechanism,—all as will be described in detail.

Needle actuating mechanism.—The needle, 105 which is of the hooked, oscillatory type, is indicated at 10, (Figs. 3, 4 and 16). Said needle is mounted in a carrier 11 in any suit-

able way and oscillated, through a link 12, by a lever 13, which is fulcrumed on a stud 14, projecting from the head A. The lever 13 is actuated by a cam 15, which is keyed to the driving-shaft 16 mounted in the head A.

5 Awl actuating mechanism.—Referring to Fig. 5, it will be seen that the awl 50 is of the oscillatory type. It receives in addition to its oscillating motion, a side thrust which effects the feeding of the work, and which, together with the oscillating motion, produces a form of four-way feed. The awl is clamped to a carrier 51, as shown in Fig. 7. The supporting end of the awl is beveled on one edge 15 so that a cross-section thereof is triangular. The beveled edge occupies a beveled groove 511 formed in the carrier to receive it, and the awl is forced into said groove by a clamping plate 512 which is pressed upon its upper edge by a screw 513 threaded into the carrier. The formation of the awl and groove prevent the former from twisting in the latter and becoming out of line, and enable the clamping-plate 512 to so wedge them together 20 that they are held by the greatest possible friction. Said carrier is oscillatably mounted on a sleeve 510, which in turn is mounted on a stud 52 projecting from the head A, and on which the needle-carrier 11 is also 25 mounted. The carrier 51 is provided with a segmental rim 53, which slides in a guide 54 formed on a block 55. An arm 56 projects from the block 55 and supports at its end the sleeve 510, with which it has a screw-thread connection. A stud 57 projecting from the 30 needle-carrier 11 occupies a hole 58 formed in the awl-carrier 51. This same stud forms the connection between the needle-carrier and the link 12, so it is evident that the oscillation imparted to the two carriers mounted on the same axis is simultaneous and uniform. The needle and awl, however, are mounted on opposite sides of the axis of 35 rotation and point in opposite directions. A suitable space is allowed between the two points so that as either one is entering the work, the other has left it. A flanged segmental guide 59 is affixed to the head, for 40 the purpose of guiding and bracing the needle-carrier.

50 Referring to Fig. 5, it will be seen that the block 55 is mounted and adapted to slide on a rod 60, parallel to the axis of rotation of the carriers 12 and 51. One end of said rod is secured to the head A and the other end to a bracket 61 secured to the head. The bracket 61 is formed with a slot 62 in which is set an adjustable stud 63. Said stud occupies a slot 64 formed in a lever 65 of which it constitutes the fulcrum, (see Figs. 2, 5 and 8). On one end of the lever 65 is a roller 66 which rolls in a cam 67 keyed to the shaft 16. The other end of the lever is connected by a bolt 68 to the sliding block 55. The throw of the 65 cam 67 transmits to the block 55 a recipro-

cating motion on the rod 60. The block 55 carries the awl-carrier 51 which has a sliding axial connection with the needle-carrier 11, and it has already been shown that the awl-carrier is free to oscillate in said block. The 70 cams 15 and 67 are so timed that the awl 50 is oscillated to enter the work. It is advanced axially to alinement with the needle 10, oscillated in the opposite direction so as to leave the work, and finally retracted axially from the needle to its original position, thus completing a four-way motion. The feeding motion of the awl may be varied by shifting the fulcrum 63 in the slot 62, thus giving more or less throw to the lever 65. 80

Looper mechanism.—While no specific looper-actuating mechanism is an essential feature of the present invention, I have shown herein a novel form of mechanism which I consider to be an improvement over the prior art and to contribute to the most perfect embodiment of my invention in a shoe-sewing machine. (See Figs. 9, 10, 11 and 12). The looper 70 is shown as secured to one end of a bell-crank arm 71, which is pivoted at one end of a lever 72 by a stud 73. The lever 72 is pivoted by a stud 74 to an ear projecting from the head A, and is provided with a cam-roller 75 at its rear end. For the sake of rigidity the lever 72 is provided with an elongated bearing 77 in which the stud 74 is located, (see Fig. 12). The elongation is shown as turned down and upon it is mounted a secondary lever 78, which together with the lever 72 is retained by the head of the 95 stud 74. On the rear end of the lever is a cam-roller 79 which lies approximately below the cam-roller 75. The rollers 75 and 79 occupy cam-paths 76 and 80 formed in the periphery of a cam-disk 81, which is keyed to the shaft 16. The paths 76 and 80 form in reality but one groove, but the groove is divided into the two concentric paths whose side walls deviate slightly laterally. The path 76 is inside the path 80 but as the deviation of the two is less than the difference in width, they do not conflict. The forward end of the lever 78 is provided with a segment of gear-teeth 82, which mesh with a segment of gear-teeth 83 formed on the rear 100 of the arm 71. Lateral motion is imparted to the looper 70 by the cam 76, but said looper, being substantially at a right angle to the radius of the segment 83, receives from the cam 80 a back-and-forth motion, which, 105 combined with the lateral motion, causes the looper to encircle the needle. After encircling the needle, the looper is caused to dart to a position tangent to the arc of the needle, so that the thread which the needle is drawing through the "between substance" has a direct pull from the looper, as shown in Fig 9 by the dotted lines. 110

Thread finger mechanism.—The mechanism for actuating the thread-finger 46 may be 115

- of any convenient form, the one shown being very similar to those heretofore employed. The thread-finger projects from an ear forming a part of the head, and it is caused to 5 rock therein by a link 47 connecting it to a bell-crank lever 48 fulcrumed to the head A. The lever 48 is actuated by a cam 49 keyed to the shaft 16, and is provided with the slot 480 by which connection is made with the link 47. If it is found that the thread-finger takes too much thread, its throw may be lessened by setting the connection in the slot 480 closer to the fulcrum of the lever 48. The 10 description of the operation of the thread-finger is hereinafter given in connection with the "stitch formation". It may be briefly stated, however, that the thread-finger has a single forward and two backward movements.
- 20 Having now described the needle, awl, and the looper-actuating mechanisms, I will now describe the devices which supply and deliver the thread to the looper and which include a wax-pot and various other mechanisms interposed between the source of supply and the looper.
- 25 *Wax pot.*—The wax pot is inclosed in a casing D to which steam for heating the wax is supplied through the pipe d^1 and exhausts 30 through a pipe d^2 , the said casing being provided with a nipple d^1 having a stripping plug d^2 which is, as is usual, of soft material.
- 35 *Thread tension device.*—The tension device referred to is located directly above the wax-pot and as shown in Fig. 15, comprises two fingers 89 and 90 between which the thread passes, and which are pivoted together by a pin 91. The finger 89 is swiveled to an ear 92 projecting from the head A 40 by a pin 93. The rear end of the finger 90 carries an adjustable set-screw 94, set in alinement with the pin 93. A wedge-piece 95 carried at one end of a bell-crank lever 96 is adapted to close the gripping ends of the 45 fingers 89 and 90 by entering between the adjacent ends of the pin 93 and screw 94, and forcing them apart. The tension fingers are normally held in a horizontal position by a spring 97, (see Fig. 3.) The lever 96, which 50 carries the wedge-piece 95 is mounted on the stud 14. On the forward end of said lever is a cam-roll 98 which co-operates with cam-faces 99 and 100 formed on the periphery of the cam-disk 67, (see Figs. 16, 17 and 18).
- 55 The tension-actuating mechanism above described allows the gripping fingers to yield, under tension of the spring 97, to any demand of the thread without altering the pressure produced by the wedge-piece 95. The 60 gripping and releasing of the thread by the fingers 89 and 90 is hereinafter described in connection with the stitch-forming mechanism.
- 65 *Take up mechanism.*—The thread x, before passing through the looper 70, is drawn over a yielding take-up or slack-controlling roll 84, (see Fig. 3). Said roll is attached to an arm 85 pivoted at 86 to a bracket projecting forward from the front of the head A. The arm which carries the roll 84 is normally 70 pressed forward by a spring 87.
- 75 The thread runs from the thread supply downward through the pivoted and yieldingly mounted thread-locking, thread-gripping or intermittent tension device afforded by the thread fingers 89 and 90, and which device can yield to the pull on the thread against the stress of the spring 97; and from said tension device the thread runs downward to the wax-pot D and thence upward 80 around the sheave 88 and forward around the yieldingly mounted take-up or slack-controlling roll 84, to the looper or thread-guide 70.
- 85 *Gage mechanism.*—The customary gage for 90 gaging and forming an abutment for the shoe is indicated at 17, and the back-gage, (or in case of a welt-sewing machine, the welt-guide), is indicated at 18. The gage 17 is adapted to slide in guides 19 19 and is held forward by a spring 20, (see Figs. 1 and 13). The gage 18 is similarly mounted in guides 21 21 and held forward by a spring 22. Between the gages 17 and 18, and mounted upon a stud 23 are two oppositely arranged bell-crank levers, which, when rocked about said stud, are adapted to frictionally lock or release said gages. The lower lever, which co-operates with the gage 17, is provided with an arm 24, in the free end of which is a stud 25, overlying the upper edge of said gage. The lever which co-operates with the gage 18 is similarly provided with an arm 26 in the free end of which is a stud 27 underlying the lower edge of that gage. Arms 28 and 29 extend 95 back from the arms 24 and 26 respectively, and are connected by a spring 30, which normally holds them toward each other, thus causing the studs 25 and 27 to engage the gages 17 and 18 respectively. The studs 25 and 27 being slightly in advance of the center of the stud 23, allow of a forward movement of the gages 17 and 18, but the spring 30 causes them to so bind the said gages that any backward movement causes them to 100 bind with increased force and positively lock the gages. They are preferably flattened where they bear against the gages, so that they may grip said gages more effectively.
- 105 The inner faces of the arms 28 and 29 are 110 beveled and constitute cam-faces 31 and 32. A projection 33 on one arm of a lever 34, fulcrumed upon a stud 35, is adapted to enter between the faces 31 and 32 and force them apart, thus disengaging the studs 25 and 27 115 from the gages 17 and 18. Said lever 34 is actuated by a cam 36 keyed to the shaft 16. Fulcrumed upon the stud 35 is an additional lever 38, (see Fig. 1) in the lower end of which is provided a slot 39. Said slot is adapted 120
- 125 130

to receive the connecting stud 40 in one end of a link 41. The other end of the link 41 is pivoted by a stud 42 to a sliding block 43 which is mounted near the rear end of the 5 gage 18. The upper side of the block 43 is normally held forward by the tension of a spring 45, which is connected to the rear guide 21. When the cam 36 causes the releasing of the gages 17 and 18, a cam 37, 10 keyed to the shaft 16, actuates the lever 38 to impart a rearward thrust of the link 41 and block 43, which is made to bind on the gage by the opposing tendencies of said link and the spring 45, thus retracting the gage. 15 The return of the block 43 is immediate and positive with that of the lever 38, but the gage 18, as previously stated, is returned by the spring 22 when the pressure ceases. A set-screw 44, projecting from the rear end of 20 the gage 18 is adapted to limit the forward movement of said gage by impinging against the block 43.

Provision is made for imparting to the block and consequently to the gage 18, more 25 or less throw, as required. The slot 39, in the arm 38, is formed on an arc of which the stud 42 is the center. Hence, by setting the stud 40 nearer to the rock-shaft 35, the effective radius of the arm 38 will be correspondingly lessened, and vice versa.

The cams 36 and 37 are so timed that they cause the releasing of the gages 17 and 18 and the retraction of said gage 18 only while the awl mechanism hereinbefore described is engaged in advancing the work for the next stitch.

Stitch formation.—The stitch-formation is best illustrated by Figs. 19 to 22. Fig. 19 shows the mechanism as it appears after the 40 completion of one stitch, and as it is about to begin the next. A shoe to be sewn is presented to the machine when the parts are in such position that the thread-finger 46 and the needle 10 are retracted from each other, 45 and the thread x is not clamped between the fingers 89 and 90. In this figure, the needle 10 is shown as about to enter the hole next in advance of the loose previous stitch looped about its shank. At this time the thread-finger 46 lies under the thread between the looper and the source of supply, but is not in contact with it. As the shaft 16 rotates, the needle is caused to pierce the "between substance", as shown in Fig. 20, at which time 50 the thread-finger has drawn up most of the surplus thread from the previous loop around the shank of the needle. The supply-thread is at this time clamped between the fingers 89 and 90 so that the thread-finger will not draw in fresh thread instead of taking up the slack. It will be seen so far that the previous loop has not been pulled tight about the needle, as is common in some machines, 55 but that the stitch is left in a somewhat slackened condition, to be set by the needle

just before it reaches the limit of its backward movement. A further rotation of the shaft 16 causes the parts to assume the position shown in Fig. 21.

The looper is shown as completing a loop 70 of thread about the barb of the needle, during which the thread is free to pass between the fingers 89 and 90 which are now open. The thread-finger 46, however, has returned part-way from the position shown in Fig. 20, 75 thereby contributing toward the new loop only a portion of the thread drawn off from the previous loop and correspondingly lessening the demand on the fresh thread.

Fig. 22 shows the position of the parts as 80 the cycle of movement is completed. As shown in this figure, the needle has drawn the last-formed loop through the "between-substance". The supply-thread is now once more clamped by the fingers 89 and 90, 85 thereby subjecting the fresh thread to the increased tension. The thread-finger has made its second receding or return movement and has returned to its original position, thereby giving up to the needle the remainder of the 90 thread drawn from the previous loop, and the looper has darted to a position tangential to the arc of the needle, so that the thread, in being drawn through the "between-substance", has a direct pull on the looper which 95 is tangential thereto and consequently does not tear the work or pull through the barb of the needle, and chafe. In this position, the needle exerts considerable tension on the loop hooked over the barb, consequently the 100 tension is transmitted to the previous loop which is thereby pulled tight to set the stitch. If, however, the free supply of thread is not enough, the spring 97 allows the clamping fingers which clamp the supply of thread to 105 yield under tension to any additional demand of the needle, rather than break the thread or tear the work. The needle, immediately after setting each stitch, advances a fraction of an inch and rests there while the 110 work is being fed forward another step. This movement of the needle relaxes the tension of the loop connected thereto, so that the feeding movement is perfectly free and smooth, and the work is not dislocated for 115 the next stitch.

Having thus explained the nature of the invention and described a way of constructing and using the same, although without attempting to set forth all of the ways in 120 which it may be made, or all of the modes of its use, I declare that what I claim is:

1. In a chain-stitch wax-thread sewing machine, the combination with a stitch-forming mechanism comprising a hooked 125 needle and a looper or thread-guide, of a thread-finger arranged to engage the thread between said looper or thread-guide and said needle, means for operating said thread finger to cause the same to draw off a loop of 130

slack thread at the formation of each stitch prior to the time when the looper or thread-guide carries the thread about the needle, and for causing said thread finger to deliver 5 part of the slack thread, thus drawn off, during the time when the thread guide or looper is carrying the thread around the needle, and to deliver the remainder of said slack thread during the time when the needle is drawing 10 a loop of thread through the material and through the previously formed loop of the chain-stitch seam.

2. In a chain-stitch wax-thread sewing machine, the combination with a stitch-forming mechanism comprising a hooked needle and a looper or thread guide, of a slack-forming thread finger, and means for imparting to said thread finger a single slack 15 drawing-off movement and two distinct delivery movements during the formation of each stitch, one of said delivery movements being timed to furnish slack thread to the said looper or thread-guide, and the other of said movements being timed to furnish slack 20 thread to the said needle.

3. In a chain-stitch sewing machine, the combination with a curved hooked needle and means for oscillating the same in the arc of a circle, of a looper or thread-guide, a pivoted arm on which said looper or thread-guide is mounted, and which is provided with a rack, a lever to which said arm is pivoted, a second lever having a rack engaging the said first-named rack, and means for 30 positively operating both of said levers to cause the looper or thread-guide to carry the thread around said needle and lay it in the hook thereof.

4. In a chain-stitch sewing machine, the combination with a curved hooked needle 40 and means for oscillating the same in the arc of a circle, of mechanism for looping the thread around and laying it in the hook of said needle, said mechanism comprising a carrying lever, an actuating lever mounted 45 upon the same pivot with said carrying lever, and extending in the same directions from said pivot, a looper arm pivoted at the end of said carrying lever, a looper mounted on said arm, connections between said looper-arm 50 and said actuating lever whereby the said looper arm may be oscillated relatively to its carrying-lever by oscillation of the said actuating lever, and means for oscillating said carrying-lever and actuating lever independently.

5. In a chain-stitch shoe sewing machine, the combination with a stitch-forming mechanism comprising a curved oscillatory hooked needle, of an oscillating carrying lever, a looper arm pivoted to one end of said oscillating lever, a gear segment on the rear end of said looper arm, a secondary or actuating oscillating lever having a gear segment 60 intermeshing with the first-mentioned segment, and means for oscillating the said levers to cause the looper to encircle the needle and lay its thread in the hook thereof and then move to a position tangential to the arc 65 in which said needle oscillates.

In testimony whereof I have affixed my signature, in presence of two witnesses.

JOHN J. HEYS.
